UNITED STATES PATENT OFFICE.

MARY P. FITZGERALD, OF PORTLAND, OREGON.

DESIGN FOR A STAMP, PICTURE, AND POST-CARD HOLDER.

42,936.

Specification for Design.

Patented Aug. 27, 1912.

Application filed June 21, 1911. Serial No. 634,640. Term of patent 7 years.

To all whom it may concern:

Be it known that I, MARY P. FITZGERALD, a citizen of the United States, residing at Portland, in the county of Multnomah and State of Oregon, have invented a new, original, and ornamental Design for a Stamp, Picture, and Post-Card Holder, of which the following is a specification, reference being had to the accompanying drawing, forming part thereof.

The figure is a front view of the holder showing my new design.

I claim:

The ornamental design for a stamp, picture and post-card holder, as shown.

In testimony whereof I have signed my name to this specification in the presence of two subscribing witnesses.

MARY P. FITZGERALD.

Witnesses:

M. STEFFEN,
